FIG. 2

ANALOG TO DIGITAL CONVERSION BY SUBRANGING WITH MULTIPLE LEVEL REDUNDANT ERROR CORRECTION

BACKGROUND OF THE INVENTION

The present invention relates broadly to an analog to digital converter apparatus and in particular to a subranging analog to digital converter with multiple level redundant error correction.

In the prior art various techniques and schemes have been utilized to increase the speed of analog to digital converters. Analog to digital converter can usually be classified into groups. One group includes high speed parallel converters in which the several digital bits are formed more or less simultaneously. The high speed of operation is obtained here at significant expenditures. The converters of the second group operate by successive approximation; progressively synthesized analog equivalents of progressively formed digital signals are compared individually with the analog information signal.

A digital correction scheme which is known in the prior art as single level correction, has been used with a subranging converter of three or more subrange stages. This technique is used to overcome the basic limitations in the comparator threshold accuracies and the interim D/A amplifier settling times. Single level correction will approximately double the operating speed of an equivalent converter that doesn't utilize the technique. A marked improvement in the speed of analog to digital converter is achieved by the present invention with multiple level correction as compared with the single level correction technique.

SUMMARY

The present invention utilizes an analog to digital converter which comprises a four stage block of multi-element comparators using a level correction technique to achieve full stage subranging of multilevel inputs. A complete 11 bit word is generated by combining the output of the four stages. The first section generates a 3 bit word, the second section generates the next 3 bits, the third section generates the next 3 bits, and the fourth section generates the last 2 bits. Synchronization of the outputs of the four comparator sections provides time alignment in a final output register thus creating the complete 11 bit word.

It is one object of the invention, therefore, to provide an improved analog to digital converter apparatus utilizing a four stage subranging converter with multiple level error correction.

It is another object of the invention to provide an improved analog to digital converter apparatus having a substantially more rapid acquisition of the subrange words, thus increasing the speed of the overall conversion.

These and other advantages, features and objects of the invention will become more apparent from the following description taken in connection with the illustrative embodiment in the accompanying drawings.

BRIEF DESCRIPTION OF THE DRAWINGS

FIG. 1 is a block diagram of the analog to digital converter apparatus in accordance with this invention,

FIG. 2 is a timing diagram of signals generated within the analog to digital converter apparatus,

FIG. 3 is a graphic representation of an ideal input voltage to the converter apparatus versus time, and

FIG. 4 is a graphic representation of an input voltage to the converter apparatus that varies with time.

DESCRIPTION OF THE PREFERRED EMBODIMENT

Referring now to FIG. 1, there is shown an 11 bit, 2 MHz word rate converter apparatus utilizing subranging with digital error correction. The subranging mechanism for this converter generates the 11 bit word in four sections. The first section A generates a 3 bit word (SIGN, MSB, MSB-1). The second section B generates the next 3 bits. The third section C generates the next 3 bit word, and the fourth section D generates the last 2 bits (LSB +1, LSB). These groups of 3, 3, 3, and 2 bits are aligned in time in the final output register 10 creating the complete eleven bit word.

The conversion process is as follows: The input video 20 which is scaled from ± 8.188 to ± 2.047 V, is sampled at the beginning of a 500 nsec range bin and is converted in the four stages A, B, C and D with a conversion time of approximately 125 nsecs per stage.

The first section A determines the word in the first 3 bits (SIGN, MSB, MSB-1) by dividing the dynamic range ($\pm 2,047$ mv) into eight equal segments with seven voltage comparators 12. The magnitude of a particular input signal is sensed by these comparators. Once the comparators 12 determine which segment 30 contains the input signal, a voltage proportional to the lower bound of that segment is subtracted from the input signal in the section A residue amplifier 14.

The outputs of the comparators 12 are defined such that if the input voltage exceeds (more positive) the 35 reference voltage of a comparator, the output of that comparator will be false. Once the input voltage has settled within accuracy limits (± 128 mv) determined by the self correction (redundancy) requirements, the 40 outputs of the comparators 12 are latched. Once the section A outputs are latched, the A Vres equation will be used to determine the output voltage of section A Residue Amplifier 14.

$$A \text{ Vres} = -2 (\text{Vin}) - NA (1024) + 3584$$

45 where NA = the number of comparators switched in the true state, not counting AC0 or AC8 since they are used only for gross overvoltage sensing. The output of the Section A, Residue amplifier 14 is the input to the Section B Comparators 16 and Residue card 18.

50 The Section B Comparators 16 contains eleven comparators biased as shown in Table 1 shown below.

Table 1

	Ex 2	
BC00	+ 640 mv	
BC0	+ 512 mv	
BC1	+ 384 mv	
BC2	+ 256 mv	
BC3	+ 128 mv	
BC4	0 V	
BC5	- 128 mv	
BC6	- 256 mv	
BC7	- 384 mv	
	Ex 1	
BC88	- 512 mv	
BC88	- 640 mv	

65 The outputs of the comparators are defined as follows:

If the input voltage (A Vres) exceeds (more positive) the reference voltage, the output of that comparator

Section C

Data	Correction Command
000	No Corrections
CVres = $-8(-432) - 9(1024) + 5632$ = $+3456 - 9216 + 5632$	
CVres = -128 mv	

Table 4 above shows Comparators DC88 – DC6 False. DC4–DC00 True.

Section D

Data	Correction Command
10	No Correction
Section A	Summary of Output Conditions
Section B	Section C
110 No Over-Voltage	111 No Correction
Section D	10 No Correction

The Example 1 demonstrates the operation of the converter assuming an idealized video input. Example 2 will be more realistic in that the amplitude of Vin will be changing with time. This will necessitate a recalculation of the residue amplifier outputs each time a comparison is made.

For value of Vin shown in FIG. 4, Table 2 shows Comparators AC0 – AC7 False, AC8 True. NA = 0. This condition decodes to the binary word 111. Note: The decoded word is in error by 1 bit.

Section A

Data	Correction Command
111	No Overvoltage Condition

Using the value of Vin at 'B' comparators, Latch Time
AVres = $-2(1,461 + 1) - (1,024) + 3,584$
AVres = $-2,924 + 3,584$
AVres = $+660 \text{ mv}$

Table 1 above shows Comparators BC88 – BC00 False. No comparators in the True state. NB = 0. This condition generates a subtract 2 command. As described in "Rules for Digital Correction," this condition will force the decoded word to 110 and generate a subtract 1 command to Section A.

Section B

Data	Correction Command
110	Subtract 1 from Section A

Using the value of Vin at 'C' comparators latch time, AVres is recalculated to solve for BVres.

$$\begin{aligned} \text{AVres} &= -2(1,478 + 1) - 0(1,024) + 3,584 \\ \text{AVres} &= -2,958 + 3,584 \\ \text{AVres} &= +626 \text{ mv} \\ \text{BVres} &= -8(+626) - 0(1,024) + 5,632 \\ \text{BVres} &= -5,008 + 5,632 \\ \text{BVres} &= +624 \text{ mv} \end{aligned}$$

Table 3 above shows Comparators CC00 – CC8 False. CC88, True. NC = 1. This condition generates an Add 1 command. As described in "Rules for Digital Correc-

tion," this condition will force the decoded word to 000 and generate an Add 1 command to Section B.

Section C

5	Data	Correction Command
	000	Add 1 to Section B

Using the value of Vin at 'D' comparators latch time, 10 AVres and BVres are recalculated to solve for CVres.
AVres = $-2(1,476 + 1) - 0(1,024) + 3,584$
AVres = $+630$
BVres = $-8(630) - 0(1,024) + 5,632$
BVres = $+592$
CVres = $-8(592) - 1(1,024) + 5,632$
CVres = $-4,736 - 1024 + 5,632$
CVres = -128 mv

Table 4 above shows Comparators DC88 – DC6 False. DC4–DC00, True.

Section D

20	Data	Correction Commands
	10	No Correction
Section A	Summary of Output Conditions	
Section B	Section C	Section D
111 No Overvoltage	110 Subtract 1 from A	000 Add 1 to B
		10 No Correction
	Final Output Word	
110	111	000
		10

30

The final output word agrees with the idealized output for Example 1. This example demonstrates how the redundancy information is used.

35 The various elements and devices which comprise the present invention are available from the following source. For example, the comparator A and its associated binary decode matrix are available as a unit under part number 1599271 from Hughes Aircraft Corp., Fullerton, Calif. 92634. The section B and C comparators respectively and their associated binary decode matrix are available under part number 1599272 from Hughes Aircraft Corp., Fullerton, Calif. 92634. The section D comparator and its binary decode matrix is available under part number 1599273. The following components are also available from Hughes Aircraft Corp., Fullerton, Calif. 92634 under the following part numbers as specified, for example; the residue A unit comprising the seven analog switches, the offset — 3584, and the A residue amplifier under part number 1599275; the residue B unit and residue C unit both respectively comprising 11 analog switches, the offset — 1408 and the B and C residue amplifier respectively under part number 1599276; the digital correction unit comprising the error command transfer logic, the binary word registers, the command registers, the digital error correction, and the output register under part number 1599279; the scale amplifier has part number 1599281; and the sample in hold has part number 1599278. All of the above components are available under the given part numbers from Hughes Aircraft Corp., Fullerton, Calif. 92634.

60 Although the invention has been described with reference to a particular embodiment, it will be understood to those skilled in the art that the invention is capable of a variety of alternative embodiments within the spirit and scope of the appended claims.

We claim:

1. An analog to digital converter apparatus with digital error correction comprising in combination:
  - an analog to digital converter having four stages to generate an 11 bit word, said analog to digital converter receiving an input voltage signal, said first state generating a 3 bit word, said second and third stages each generating a 3 bit word, said fourth stage generating a 2 bit word, said analog to digital converter providing an output binary count, said second, third and fourth stages including a plurality of redundancy comparators, (said plurality of redundancy comparators respectively checking the output of the previous stages) said plurality of redundancy comparators respectively generating a correction command for the affected stage upon sensing an error therein,
  - a plurality of decode logic units respectively connected to said four stages of said analog to digital converter to receive the respective word bit, said plurality of decode logic units respectively decoding said output binary count, said plurality of decode logic units providing a binary word output, said plurality of decode logic units respectively including error command logic units connected respectively to said plurality of redundancy comparators of said second, third and fourth stages of said analog to digital converter, said error command logic units respectively providing an error correction signal upon receipt of said correct command from one of said plurality of redundancy comparators,
  - an interim holding register connected to said plurality of decode logic units to store said binary word output,
  - a digital error correction unit connected to said interim holding register to receive said binary word output, said digital error correction unit receiving error correction signals from said plurality of decode logic units, said error correction signals being

utilized by said digital error correction unit to correct said binary word output, and
 an output register connected to said digital error correction unit to receive said binary word output, said output register aligning said binary word output in time, said output register providing a final 11 bit output word.

2. An analog to digital converter apparatus as described in claim 1 wherein said first stage of said analog to digital converter comprises:
  - seven voltage comparators to determine the first segment of said 11 bit word, said first segment being applied to a first residue amplifier, said first residue amplifier subtracting a voltage proportional to the lower bound of said first segment from said input voltage signal, said first residue amplifier providing a first output voltage,
  - said second stage of said analog to digital converter comprising eleven voltage comparators to determine the second segment of said 11 bit binary word, said second stage receiving said first output voltage, said second segment being applied to a second residue amplifier, said second residue amplifier receiving said first output voltage, said second residue amplifier providing a second output voltage,
  - said third stage of said analog to digital converter comprising eleven voltage comparators to determine the third segment of said eleven bit binary word, said third stage receiving said second output voltage, said third segment being applied to a third residue amplifier, said third residue amplifier receiving said second output voltage, said third residue amplifier providing a third output voltage, and
  - said fourth stage of said analog to digital converter comprising seven voltage comparators to determine the fourth segment of said 11 bit binary word, said fourth stage receiving said third output voltage, said fourth stage generating a 2 word bit output.
